George C. Shaffer

ATTORNEY.

UNITED STATES PATENT OFFICE.

RALPH GREGORY, OF KANSAS CITY MISSOURI, ASSIGNOR TO OIL WELL RECLAMATION COMPANY, OF CHICAGO, ILLINOIS, A CORPORATION OF DELAWARE.

OIL-WELL PUMP.

1,317,921.

Specification of Letters Patent.

Patented Oct. 7, 1919.

Application filed February 20, 1919. Serial No. 278,209.

To all whom it may concern:

Be it known that I, RALPH GREGORY, a citizen of the United States, residing at Kansas City, in the county of Jackson and State of Missouri, have invented certain new and useful Improvements in Oil-Well Pumps, of which the following is a specification.

This invention relates to oil well pumps and more especially to what I term self-contained pumps for pumping shallow wells, and my object is to produce a simple pump susceptible of use in connection with an oil well pumping apparatus on which I filed application on January 20, 1919, Serial Number 272,152.

To this end the invention consists in certain novel and useful features of construction and organization of parts as herein-after described and claimed; and in order that it may be fully understood, reference is to be had to the accompanying drawing, in which:

Figure 1, is a fragmentary vertical section of an oil well pump embodying the invention.

Fig. 2, is a section on the line II—II of Fig. 1.

Fig. 3, is a section on the line III—III of Fig. 1.

In the said drawing 1 indicates the casing and 2 the cavity at the lower end of said casing, of an oil well.

The pump proper is constructed as follows: 3 indicate sections of tubing connected together by couplings 4 so as to form a pump body of sufficient length to extend from or above the ground level nearly to the bottom of the cavity 2, and secured to 40 and depending from a similar coupling 4 secured to the lowermost tube section 3 is a valve casing 5, containing a removable valve seat 6 for a ball-valve 7 or equivalent check valve, said seat also forming an attachment for a depending perforated tube or strainer 8 to exclude particles foreign to oil from the valve casing.

9 indicates tubing forming what I term the barrel of the well, and secured to and 50 extending from the casing 5 to a point preferably above the oil level in the well, and said barrel is provided adjacent its lower end with perforations 10 to permit oil to pass from said barrel into the body 3 or 55 from the latter into said barrel. Just above

the perforations 10 the barrel is provided with a check valve 11 adapted for opening upward, and at its upper end the barrel is connected by a coupling 12 with a depending pipe 13 adapted to extend up through the top of the well for distribution of the oil, and the space between the discharge pipe 13 and the body 3 at a point near the coupling 12 is sealed by a collar or ring 14.

The coupling has a perforated diametric portion 15 which does not close communication between the barrel 9 and discharge pipe 13, but is for establishing communication between the interior of the body portion 3, and an air tube 16 extending down into the well and fastened at its lower end to said coupling 12.

In operation, fluid under pressure is forced down through tube 16 so that it shall lower the level of the oil in the body portion 3, and hence discharge all of the oil standing in both the body portion and the barrel above the level of perforations 10, because the oil standing in the body portion above the level of said perforations is forced into the barrel and upward through the latter and the discharge pipe 13, the check valve 11 moving upward from its seat to accommodate this operation.

When the pressure of fluid is cut off, the valve 11 reseats and thus retains a charge of oil within the barrel and discharge pipe for discharge upon the next introduction of fluid under pressure through said tube 16.

It will be apparent that the oil well described is self-contained, in that it may be used regardless of the presence or absence of the well casing 1, that is the pump may be inserted in a hole not equipped with a casing.

From the foregoing it will be apparent that I have produced a pump of the character described which possesses all of the features pointed out as desirable, and while I have illustrated and described the preferred construction, it is to be understood that I reserve the right to make all changes falling within the principle of construction and mode of operation involved and the spirit and scope of the appended claims.

I claim:

1. An oil well pump, comprising a tubular body, a casing closing and depending from the lower end of said body, a check valve in said casing, a tubular barrel within the body and communicating at its lower end with

110

- said casing above the check valve, and communicating above the casing with said body, a discharge pipe in the body, a coupling uniting the upper end of the barrel with the lower end of the discharge pipe, said coupling having a passage leading to the interior of said body, and an air tube extending down through the discharge pipe and communicating with the said passage.
- 10 2. An oil well pump, comprising a tubular body, a casing closing and depending from the lower end of said body, a check valve in said casing, a tubular barrel within the body and communicating at its lower end with said casing above the check valve, and above the casing with said body, a check valve in the barrel above the point of communication thereof with said body, a discharge pipe in the body, a coupling uniting the upper end of the barrel with the lower end of the discharge pipe, said coupling having a passage leading to the interior of said body, and an air tube extending down through the discharge pipe and communicating with the said passage. 25

In testimony whereof I affix my signature.

RALPH GREGORY.
